UNITED STATES PATENT OFFICE.

JULIUS RITTER, JR., OF RACINE, WISCONSIN, ASSIGNOR TO HARTMANN TRUNK COMPANY, OF RACINE, WISCONSIN, A CORPORATION OF WISCONSIN.

COMBINED TOP AND FRONT-DOOR LOCK.

Application filed September 12, 1927. Serial No. 218,986.

This invention relates to improvements in combined top and front door locks.

Wardrobe trunks are usually divided vertically into two parts to form a wardrobe section and a drawer section. The two sections are hinged together to swing horizontally to open or closed position, and one of the sections is formed with an upper open end closed by a top cover. The wardrobe section is provided with garment hangers for suspending outer wearing apparel thereon, and the other section is provided with drawers for holding other articles of wear.

Trunks of this type are often left in open position in rooms, with the result that the garments in the wardrobe section are exposed to dust and surreptitious removal, unless the sections are closed and locked.

It is one of the objects of the present invention to overcome the before mentioned objectionable features, and provide a wardrobe trunk having inner top and front covers for the wardrobe section, and locks for said covers which will protect the contents of said section.

A further object of the invention is to provide a combined top and front door lock mounted on the inner top cover and the front door and arranged so that the movement of the inner top cover towards its open or closed position will unlock or lock the front door.

A further object of the invention is to provide a combined top and front door lock which is of simple construction, is strong and durable and is well adapted for the purpose described.

With the above and other objects in view, the invention consists of the improved combined top cover and front door lock and its parts and combinations, as set forth in the claims, and all equivalents thereof.

In the accompanying drawing in which the same reference characters indicate the same parts in all of the views:

Fig. 1 is a front of a wardrobe trunk shown in open position and provided with the improved combined top and front door lock;

Fig. 2 is a vertical sectional view of the upper portion of the trunk with the parts shown in closed position;

Fig. 3 is a front view of a portion of the trunk showing the inner door and the top cover in closed position;

Fig. 4 is a front view of a fragmentary portion of the two trunk sections;

Fig. 5 is a front view of a fragmentary portion of the upper part of the trunk, the inner door being shown in closed position;

Fig. 6 is a central vertical sectional view through the upper portion of the wardrobe section of the trunk showing the top cover in closed position; and

Fig. 7 is a sectional detail view taken on line 7—7 of Fig. 3.

Referring to the drawings, the numeral 8 indicates the wardrobe section and 9 the drawer section of a wardrobe trunk. The two sections are hinged together to swing horizontally to open or closed position; and the wardrobe section is formed with an open top 8' which is closed by a top cover 10 hinged to the upper forward edge of the drawer section 9. Said cover swings forwardly over the open end of the wardrobe section when said section is in closed position. The wardrobe section is provided with opposite side rails 11, garment hangers 11' slidably mounted thereon, and a garment retainer 12, while the other section 9 is provided with a plurality of slideable drawers 13 for holding other articles of wear.

An inner front door or cover 14 connected to the inner edge portion of the wardrobe section which is hinged to the drawer section 9 by hinges 15, is arranged to cover the front open portion of the wardrobe section. An inner top cover 16 connected to the upper edge portion of the front door 14 by a piano hinge 17 is adapted to extend over and cover the upper open end of the wardrobe section when the front door 14 is in closed position.

When in open position, the top cover 16 may be swung outwardly and downwardly on the outer side of the front door 14, as shown in Figs. 1 and 5. The outer edge portion of the wardrobe section 8 is provided with a vertically extending frame member 18 having elongated slots 19 formed therein which are adapted to receive hook shaped bolts 20 mounted on the reciprocal locking bar 21. Said bar 21 is reciprocally connected to the front door, and at its upper end is pivotally connected to the top cover 16 by a link 22, so that when the front door is closed and the top cover is swung to closed position, the bolts 20 will be moved downwardly into locking engagement with the slotted portions 19 of the frame member 18.

100

105

110

The frame member is also provided with a lower elongated slot 19, which receives the guide bolt 20' when the front door 14 is swung to closed position to aline the door 5 vertically with the trunk section and to prevent surreptitiously disengaging the bolts from the slotted portions of the frame.

The inner top cover 16 of the wardrobe section is provided with a keyed locking 10 member 23 adjacent its hinged edge which has an elongated bolt 24, and said bolt extends through the cover to the opposite edge thereof, and is adapted to lockingly engage the escutcheon plate 25 secured to the rear 15 upper edge portion of the wardrobe section, as shown in Fig. 6. The locking member 23, when the cover is in closed position, extends through an opening 25' formed in the inner front door 14 to permit the use of a 20 key (not shown). A coiled spring 24' surrounding the bolt, yieldingly holds the bolt in its locking position. To unlock the top cover, the key is turned to unlocked position, and the bolt lever 26 is then pulled upwardly 25 to release the bolt from the escutcheon plate 25. When in unlocked position, the top cover may then be swung upwardly, and in swinging, the link connection 22 between the 30 top cover and the reciprocal bar 21 will slide the bar upwardly and unlock the bolts 20 from the frame member 18, so that said door may be swung to open position. The link 22 has a slot and pin connection 22' with the front door 14 to permit the top cover being 35 swung against the outer side of the front door, as shown in Figs. 1 and 5.

The front door carries a shoe box 27, and the wardrobe section is provided with a guard 40 member 28 which is hinged to the inner side of the wardrobe section 8 adjacent the trunk section hinges, and is engaged by the inner side of the shoe box and is moved to closed 45 position thereby. Said member 28 serves as a guard to prevent apparel supported from the hangers from entering between the hinged side of the shoe box and the adjacent side of the trunk section. A cushion 29 is mounted on the lower side of the inner top 50 cover, and is adapted to engage the garment hangers 11' and the garments draped thereon. The outer top cover 10 is also provided with a cushion 30 which bears against the inner top cover to reinforce the same when in closed position.

55 From the foregoing description, it will be seen that the combined top and front door lock is of very simple construction and is well adapted for the purpose described.

What I claim as my invention is:

60 1. The combination with a wardrobe trunk formed of two hinged together sections swingable horizontally to open position, one of said sections having an open top and front and an inner top cover and an inner front 65 cover, of a locking means therefor, comprising a manually controlled lock for the inner top cover, and a locking means for the inner front door actuated by the movement of the inner top cover towards open or closed position.

70

2. The combination with a wardrobe trunk formed of two hinged together sections swingable horizontally to open position, one of said sections having an open top and front and an inner top cover and an inner front door, of a locking means therefor, comprising a manually controlled lock for the inner top cover, a reciprocal locking means for the inner front door, and a connection between the inner top cover and the reciprocal locking means for moving said locking means to a locking position when the top cover is swung towards a locked position.

75

3. The combination with a wardrobe trunk formed of two hinged together sections swingable horizontally to open position, one of said sections having an open top and front and an inner top cover and an inner front door, of a locking means therefor, comprising a manually controlled lock for the inner top cover, a slotted frame member forming part of the trunk section, a bar reciprocally mounted on the inner front door and having hook like projections which lockingly enter the slots of the frame member, and a slotted link connection between the upper portion of the reciprocal bar and the top cover for actuating the locking bar to locking position when the top cover is swung towards closed position.

4. The combination with a wardrobe trunk formed of two hinged together sections swingable horizontally to open position, one of said sections having an open top and front and an inner top cover and an inner front door, of a locking means therefor, comprising a top cover locking member carried by the cover and having a locking bolt at one end and a keyed lock at its other end for locking the bolt in locked position, a reciprocal bar carried by the front door and having a projecting hook, the trunk section having a slotted member which is engaged by the projecting hook, and a link connection between the reciprocal bar and the top cover for actuating said bar to locking position when the top cover is swung towards closed position.

5. The combination with a wardrobe trunk formed of two hinged together sections swingable horizontally to open position, one of said sections having an open top and front and an inner top cover and an inner front door, of a locking means therefor, comprising a top cover locking member carried by the cover and having a locking bolt at one end and a keyed lock at its other end for locking the bolt in locked position, a bolt lever mounted in the upper portion of

the top cover between the bolt and the keyed lock for moving the bolt to unlocking position, a reciprocal bar carried by the front door and having a projecting hook, the 5 trunk section having a slotted member which is engaged by the projecting hook, and a link connection between the reciprocal bar and the top cover for actuating said bar to locking position when the top cover is 10 swung towards closed position.

6. The combination with a wardrobe trunk formed of two hinged together sections swingable horizontally to open position, one of said sections having an open top 15 and front and an inner top cover and an inner front door, of a locking means therefor, comprising a top cover locking member carried by the cover and having a locking bolt at one end and a keyed lock at its other end 20 for locking the bolt in locking position, a

coiled spring for normally holding the bolt yieldingly in locking position, a bolt lever mounted in the upper portion of the top cover between the bolt and the keyed lock for moving the bolt to unlocking position, 25 the said trunk section having elongated slots, a reciprocal bar carried by the front door and having outwardly projecting hook like bolts which lockingly enter some of the slots, a link having a pin and slot connection with 30 the upper end portion of the reciprocal bar and with an edge portion of the top cover and moved thereby, and a fixed bolt member carried by the front door and entering one of the elongated slots for guiding and holding the door in locking position.

In testimony whereof, I affix my signature.

JULIUS RITTER, JR.
